(57) **CLAIM**

The ornamental design for a necktie accessory, as shown and described.

DESCRIPTION

FIG. 1 is a top front perspective view of a necktie accessory, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top rear perspective view of the necktie accessory, shown in an open condition.

The evenly sized broken lines depict portions of the necktie accessory that form no part of the claimed design.

The alternating sized broken lines depict a boundary of the necktie accessory and form no part of the claimed design.

1 Claim, 4 Drawing Sheets
